UNITED STATES PATENT OFFICE

HARRIETTE M. CAMP, OF BOSTON, MASSACHUSETTS.

CABINET-COUCH.

1,327,941.

Specification of Letters Patent. Patented Jan. 13, 1920.

Application filed April 11, 1918. Serial No. 227,984.

To all whom it may concern:

Be it known that I, HARRIETTE M. CAMP, a citizen of the United States, and resident of Boston, county of Suffolk, Commonwealth 5 of Massachusetts, have invented an Improvement in Cabinet-Couches, of which the following description, in connection with the accompanying drawings, is a specification, like characters on the drawings represent- 10 ing like parts in each of the several views.

This invention relates to a bed or couch that has also formed in combination therewith a cabinet structure affording storage space and protection for wardrobe or other 15 household articles. To this end I provide a couch or bed with a box like supporting structure to which the couch springs are fitted and equipped with suitable drawers or doors, or both, constructed and arranged 20 to furnish completely inclosed compartments to receive and hold protectively articles of apparel or of household use. The foregoing and other objects and advantages 25 of the invention will more fully appear from the following detailed description, and the distinctive features of novelty will be pointed out in the appended claim.

Referring to the drawings:

Figure 1 is a perspective view showing 30 a cabinet couch constructed in accordance with my invention;

Fig. 2 is a horizontal section thereof on line 2—2 of Fig. 3; and

Fig. 3 is a lengthwise vertical section on 35 line 3—3 of Fig. 2.

In accordance with my invention I provide a stout cabinet box structure 10 having a top 11 which preferably overhangs the sides to some little extent as indicated at 40 11^a, this top also preferably completely covering and protecting the top of the cabinet against the entrance of vermin or any foreign matters whatsoever. To this cover 11 I fit and fix a suitable spring structure 12 and apply thereto a suitable mattress 13. The body of the cabinet 10 may be partitioned or divided in any suitable manner according to requirements but as shown I 45 provide an intermediate transverse partition 14 extending up from the base 15 which completely incloses the bottom of the cabinet, this partition thus completely dividing off one end portion of the cabinet space from the other end portion. As shown I 50 55 arrange one of these end portions to receive drawers, having for this purpose an inter-

mediate spacing and supporting board 16 so that a drawer 17 may be fitted underneath this board and another similar drawer 18 fitted in the upper space, this particular 60 number of drawers being of course illustrative. These drawers are formed so as to fit closely the space in which they operate and they are preferably fitted so as to pull out from either side of the cabinet having 65 for this purpose hand pulls 19 at each side. The sides 17^a, 18^a of these drawers fit closely into the cabinet space when the drawers are closed thus making the compartments 70 tight and secure against dust or insects. The 75 other end portion of the cabinet is shown as equipped with a series of shelves 20 and doors 21 at each side hinged at 22 to the cabinet serve to inclose and protect this space which may be devoted to cupboard 75 or like uses. The doors 21 are preferably provided at each side of the cabinet so that the cabinet as a whole is accessible from either side and thus there is no restriction 80 as to which side thereof may be positioned 85 against a wall or like backing, it being possible to reach the contents of the drawers and cupboard shelves with equal facility from either side of the cabinet. The invention is thus adaptable and well designed for use either in small apartments or cottages where the available room and closet space is limited and by reason of the 90 accessibility of the cabinet contents from either side thereof, the full width of the 95 cabinet is made readily available for use and no difficulty is experienced in arranging the couch in any way found most convenient in the room. I am aware that the invention can be embodied in other specific 100 forms without departing from the spirit or essential attributes thereof, and I therefore desire the present embodiment to be considered in all respects as illustrative and not restrictive, reference being had to 105 the appended claim rather than to the foregoing description to indicate the scope of the invention.

Having described my invention, what I claim as new and desire to secure by Letters 105 Patent is:

A cabinet-couch consisting in a cabinet box having a solid top completely covering the same and adapted to protect the contents of the box, a resilient bed structure 110 applied to said top and extending the length thereof, the interior of said cabinet being

divided transversely into storage spaces, drawers operable in certain of said storage spaces at one end of said box and slidable from either side of the cabinet, and when closed rendering the cabinet tight and protective of its contents, and doors at each side of said cabinet closing the storage space

in the other end of said box, the arrangement of said drawers and doors permitting access to the storage space of said box from 10 either side thereof at will.

In testimony whereof, I have signed my name to this specification.

HARRIETTE M. CAMP.
